UNITED STATES PATENT OFFICE.

THOMAS FLANAGAN, OF BURRITT, ILLINOIS.

STAPLE-EXTRACTOR.

SPECIFICATION forming part of Letters Patent No. 314,116, dated March 17, 1885.

Application filed February 27, 1884. (No model.)

To all whom it may concern:

Be it known that I, THOMAS FLANAGAN, a citizen of the United States, residing in the town of Burritt, in the county of Winnebago 5 and State of Illinois, have invented a new and useful Staple-Extractor, of which the following is a specification.

This invention relates to repairing, reconstructing, and removing wire fences. Its object is to disconnect the fence-wires from their connections with the fence-posts.

It consists of a claw-pincher and a combined claw-pincher and claw-bar, all of which will be hereinafter more fully described.

15 In the accompanying drawings, Figure 1 is an isometrical representation of a claw-pincher embodying my invention, and Fig. 2 represents an application of my improvement.

My improved claw-pincher is composed, in 20 the main, of two lever-arms, A and B, of suitable dimensions. One end *a* of each arm is of curved jaw form, and the two arms A and B immediately rearward of the curved jaws cross each other, and are fulcrumed at their 25 crossing by means of a suitable rivet or bolt, *b*, passed through the parts to connect them in such a manner as to permit the parts to oscillate freely on their pivotal or fulcrum connection. These parts, so far as described, are 30 substantially the same as like parts of pinchers now in use.

The jaws *a* of the pincher are each produced in claw form, being provided centrally in their free ends with a V-formed notch, *c*, in the 35 usual claw form.

The free end of the lever-arms A is provided with a claw-arm, *d*, extending laterally to the lever-arm. This lateral claw-arm *d* is 40 of a suitable curved form, and is provided centrally with a V-formed slot, *e*, producing a claw of suitable form.

At *h* is represented a link-detent having a 45 free hinged or pivotal connection with the free end portion of the lever-arm A in such a manner as to permit the link to swing freely in its connection. The length of this link-detent and its conformation are such that its free open end will embrace the free end of the le-

ver-arm B when the jaws of the pincher are closed.

At C is represented a fence-post, to which are fixed fence-wires *k* by means of staples *n*, spanning the wire and driven into the post in the usual manner.

In the use of my improved claw-pincher 55 the claw-formed jaws are opened and are placed against the face of the post, as represented in Fig. 2, in such position relatively with the fence-wire and the staple connecting it with the post that the slot in the jaws will 60 embrace the staple on both sides of the wire, and the unslotted portion of the jaws will pass between the post and the wire on both sides of the staple. In this position the jaws, by means of the lever-arms, are closed, embracing the staple between the post and the wire, and by means of an up or down movement of the free end of the lever-arms the 65 staple will be drawn from the post, and the wire will be disconnected therefrom without injury to either the wire or staple, and may be again connected to a new post or removed and employed in other situations.

When it is found that the staples employed to fix the fence-wires in position on the posts 70 have not been driven to clamp or bind the wire to the post, which construction of fence is quite common, the claw-arm *d* will be found a convenient implement for extracting the 75 staples and disconnecting the wire from the posts.

The application of this portion of my improved extractor is also clearly represented in Fig. 2 of the drawings, in which instance

the claw is passed between the wire and the post, either upward or downward, in such a 85 manner as to receive the staple within the V-formed slot *e* in the arm, and by means of an up or down movement of the pinchers, as the ease may be, will operate to draw the staple from the post and free the wire from its fastening in a manner to permit the wire and staple to be replaced for further use.

In the use of my improved pinchers for extracting staples requiring more than ordinary force the detent-link is employed to confine 95 the free ends of the lever-arms to prevent

opening of the jaws under the strain required. The detent-link also serves to hold the jaws closed when the claw on the free end of the lever-arm A is employed, as shown and described, and serves to render the implement more convenient in handling.

I claim as my invention—

The combination, in a pincher, of jaws cen-

trally slotted in claw form, a hook-claw on the free end of one lever-arm, and a pivoted link to connect the free ends of the lever-arms, substantially as and for the purpose set forth.

THOMAS FLANAGAN.
